UNITED STATES PATENT OFFICE.

THOMAS W. BROWN, OF BELMONT, MASSACHUSETTS.

DESIGN FOR CAR-SEAT-END FRAME.

Specification forming part of Design No. 5,463, dated January 9, 1872.

To all persons to whom these presents may come:

Be it known that I, THOMAS W. BROWN, of Belmont, in the county of Middlesex and State of Massachusetts, have invented or produced a new ornamental and useful Design for a Car-Seat-End Frame; and do hereby declare the same to be represented in the accompanying drawing and to be thus described—

Figure 1 of such drawing being a front elevation, and Fig. 2 an edge view of a frame formed in accordance with such design.

In the said drawing the curved arm-rest carrier A is shown as formed in the usual manner. It is supported by a series of bars, *a a a* *b b b*. The bars *a a a* are parallel; so are the bars *b b b*; but those of one series are disposed to those of the other at angles of sixty degrees or thereabout, so as to form lozenge or parts of lozenge openings between such bars. The connected bars joined to the arm-rest carrier at its middle and extremities, as shown, are

truncated, or formed with vertical portions *c*, from the rear side of each of which a socketed projection, *d*, is extended. Two trapezoidal projections *e e* are extended from the system of bars in manner as shown, each having a socketed projection, *f*. Furthermore, the series of bars is supported by a foot-piece, *g*, and two upright standards, *h h*. The bars are paneled on their outer surfaces, there being in each panel one or more lozenges in relief, all being as represented. Besides being so formed, the system of bars is bent in manner as shown at *i k l m n o* in Fig. 2.

I claim—

The design substantially as described and represented.

THOMAS W. BROWN.
